KEY FASTENER

Warren L. Bald, Los Angeles, Calif.

Application May 30, 1945, Serial No. 596,773

2 Claims. (Cl. 70—430)

1

The object of the invention is to provide a simple device which may be slipped into a keyhole from the room side of the door, for example, and after the key has been turned to door-locking position, and which will prevent rotation of the key to the point where the door may be unlocked from the outside, and the key cannot be pushed out of the lock.

A number of devices of the general character have been proposed in the past, and the special problem is to provide a satisfactory latch element which will pass through the bow of the key and which will be carried by the primary member of the key-fastener. In the past such elements as hasp locks, hinge lock connections, hinged lug bars, and cotter pins, connected to the key-fastener by chains, have been employed. All of these arrangements are unsatisfactory, either from the standpoint of cost or from the standpoint of installation of the latch. A latch arrangement consisting of a unitary member carried by the fastener and which can be rapidly moved out of position by a single motion, ready to drop into the bow of the key by gravity, appears to be an ideal solution, and it is the specific object of the present invention to provide such a device.

The invention will be described with reference to the accompanying drawing, in which

Fig. 1 is a perspective view showing the face plate of a door lock having a key opening, the key having been turned to locking position, or with its bow somewhat horizontally of the key aperture, and my device in position, dotted lines showing the released position of the latch.

Fig. 2 shows a modified form of the key retaining device shown by Figures 1 and 3.

Fig. 3 is a top plan view.

In Fig. 1 the face plate of a door lock is shown at 1. It is formed with a keyhole at 2 to receive a key such as that shown at 3, the bit of the key, shown at 4, being in position after the key has been turned at or somewhat beyond door locking position. My key-fastener is shown in position.

My key-fastener consists of a primary member, preferably of narrow strip steel which is given a twist at the area 5 so that a blade 6 is formed and which lies substantially at right angles to the shank 7.

The shank 7 may be a straight section, as shown in Figs. 1 and 3, or it may be bent upwardly and thence forwardly to provide an overhanging section 7^x as shown in Fig. 2. In either case the shank is formed with spaced apertures to receive the latch and to enable the latch to be moved up-

2

wardly out of locking position by a straight-line single movement.

The latch may be formed of either round or flat faced rod stock. It has a vertical section 8 at the top of which there extends a horizontal section 8^x which merges into a vertical prong 8^{xx}. The base of the vertical section 8 is provided with a stop head of any suitable formation, and in the present embodiment the lower end of the latch 10 simply is bent angularly to provide the stop.

I prefer that at least one face of the latch be flattened and that the latch receiving apertures in the shank 7, or in that shank and its overhanging section 7^x of Fig. 2, be correspondingly 15 formed so that the latch will have a vertical movement only and will not swivel.

When the key is inserted in the lock and is turned to throw the bolt of the lock, my device 20 may be inserted so that its blade will lie in the position of Fig. 1. During the insertion of the key-fastener the forefinger of the operator will press the latch upward so that it will lie on the dotted line position of Fig. 1, and the latching prong will slip over the rear area of the key handle 25 bow and in register with the aperture of the latter. This is the sole operation, because when the device is released by the hand the latch will fall by gravity into latching position, as shown in Figs. 1 and 2. My device thus enables this simple 30 operation, and I prefer that the apertures in the key-fastener shank be such as to afford free and easy movement of the latch and at the same time prevent any swiveling movement thereof. I know of no key-fastener which can be operated in this 35 simple and effective manner.

It will be understood that various modifications may be made in the specific form and arrangement of the elements constituting the embodiment illustrated in the drawing, without departing 40 from the spirit of the invention. While the gravitational feature of the latch is desirable, the latch may have a slight frictional grip if desired, so that thumb pressure will move the prong into the bow of the key and thence into the prong 45 aperture.

Having described my invention, what I claim and desire to secure by Letters Patent is as follows:

1. A key-fastener comprising a vertical blade 50 twisted to form a shank which lies angularly of the blade, the shank being formed with spaced apertures, and a latch consisting of a unitary member having a vertical section formed with a stop at its lower end, the upper area of the latch 55 being bent horizontally and thence downwardly

to form a vertical prong, the first named vertical section of the latch being slidably mounted in one of said apertures, and the prong normally lying in the second aperture, movement of the latch in upward direction by pressure on the stop end effecting withdrawal of the prong from its aperture so as to clear the bow of a key.

2. A key-fastener comprising a unitary member having a blade and a shank lying angularly of the blade, the shank being formed with spaced apertures, and a latch consisting of a unitary member having a vertical section provided with a stop at its lower end, the upper area of the latch being angularly of the latch vertical section and thence extending downwardly to form a prong, the vertical section of the latch being slidably mounted in one of said apertures, and the prong normally lying in the second aperture, movement

of the latch in upward direction by pressure on the stop end effecting withdrawal of the prong from its aperture so as to clear the bow of a key.
